UNITED STATES PATENT OFFICE

BERTRAM WELLMAN, OF SCHENECTADY, NEW YORK, ASSIGNOR TO GENERAL ELECTRIC COMPANY, A CORPORATION OF NEW YORK

CIRCUIT INTERRUPTER

Application filed June 14, 1928. Serial No. 285,412.

This invention relates to circuit interrupters and the principal object is to provide improved methods and means for quickly and effectively extinguishing the arc or discharge 5 ordinarily accompanying the interruption of the circuit.

The present invention is particularly advantageous in connection with vacuum switches having circuit interrupting contacts 10 separable in a highly evacuated container, although it may be employed with limited advantages in other forms of circuit interrupters. Moreover, the invention is of special 15 advantage in interrupting direct current circuits, but may be used to obtain a quick interruption of alternating currents if desired.

With the vacuum switch type of circuit interrupter in which the contacts are separated within a highly evacuated container, the 20 interruption of alternating current circuits is most readily accomplished for the reason that the arc or discharge occurring upon separation of the switch contacts tends automatically to extinguish itself when the alternating 25 current passes through the zero point of the wave. However, in direct current circuits there is no such tendency and the ability of a vacuum switch to interrupt such circuits is correspondingly restricted.

30 Furthermore, the circuit interrupting ability of a vacuum switch in both alternating and direct current service depends to a considerable extent upon the particular material of which the switch contacts are formed. 35 This is due to the fact that two different types of electron discharge may occur upon separation of the contacts of the vacuum switch dependent upon the material of the contacts.

40 Thus a hot cathode type of emission may occur where the vacuum switch contacts are formed of a high melting point metal such as tungsten. In this case any arc or spark which is formed when the contacts are initially 45 separated or any highly localized heating of the last points of contact due to the excessive concentration of the current therein may raise the temperature of the contact material sufficiently to produce electronic emission 50 therefrom. If the continued passing of

current results in the production of sufficient heat at the cathode to maintain the contact material thereof at the emission temperature, the emission will continue indefinitely and thereby prevent the interruption of the circuit. 55 If, however, after the contacts are fully separated the heating action is insufficient to maintain the cathode material at the required temperature, the electronic emission at once ceases and the circuit is immediately interrupted. 60

On the other hand, if the contacts of the switch are of some low melting point material, such as copper, which vaporizes before the electron emission temperature is 65 reached, a relatively cold cathode type of emission may result. In this case, the initial separation of the low melting point contacts while current is flowing may also cause arcing or result in a highly localized heating of the last points of contact such that the low melting point material is raised to the temperature where the material melts and vaporizes. At the same time, as the 70 contacts are initially separated any appreciable potential drop therebetween may produce a very high voltage gradient. Even a relatively small absolute voltage drop between the contacts while still very close together may produce a gradient of the order 75 of several millions of volts per centimeter. Such a voltage gradient will draw electrons from a relatively cold metal and thus produce electronic emission between the contacts even though they are not heated to a 80 temperature sufficient to cause electronic emission of the type referred to in connection with the high melting point contact material. The electrons drawn from the low melting point material of the negative 85 or cathode contact by the high voltage gradient inevitably will collide with the molecules of metal vapor in the space between the contacts. Such collisions will ionize the metal vapor, thus producing additional electrons which join those already formed and travel under the influence of the impressed voltage toward the anode, or positive electrode. The positive ions travel towards the 90 cathode, or negative electrode, and due to 95 100

their very much greater mass, have a relatively slow movement so that positive charges accumulate in the region adjacent to the cathode. These positive charges serve to maintain a very high potential gradient at the cathode surface, thus continuing to draw out electrons even though the contacts meanwhile have been separated to a considerable distance. Thus, it will be seen that when this type of electronic emission is once initiated the current in the circuit may continue indefinitely. However, in alternating current service where the current between the low melting point switch contacts inherently passes through zero and reverses, the ionized metal vapor is quickly dissipated and the emission phenomena automatically ceases substantially as soon as the current reaches the zero value. In this way even high voltage alternating current circuits are readily interrupted by vacuum switches having contacts of low melting point material. In direct current service, there is no such reversal of current to stop the electron emission between the contacts of low melting point material and thereby interrupt the circuits.

My present invention, however, enables a vacuum switch having contacts of low melting point material quickly and effectively to interrupt direct current circuits. Briefly, this is accomplished by providing means for reducing the direct current between the vacuum switch contacts substantially to zero value or at least below the value required to sustain the arc or electron discharge after the contacts are separated. When this occurs the ionized vapor produced upon the separation of the low melting point vacuum switch contacts is quickly dissipated and thereby the electron emission phenomena is effectively stopped in substantially the same manner as occurs with alternating current circuits. The reduction of the direct current to zero or below the arc or electron discharge sustaining value preferably is obtained by connecting a charged condenser across the contacts after they have been separated sufficiently to start the electron emission phenomena so as to impress a voltage on the resulting arc or discharge between the contacts in opposition to the sustaining voltage thereof. In this way the arc or discharge between the vacuum switch contacts is effectively extinguished. When once extinguished the electron emission phenomena cannot restart since the contacts are separated.

Furthermore, in accordance with the present invention I provide an improved arrangement for automatically charging the condenser and connecting it to the switch contacts.

From another viewpoint, the connection of the charged condenser across the vacuum switch contacts serves to divert the current

from the arc or discharge between the contacts through a shunt circuit including the condenser. The arrangement is such that at the instant of connecting the charged condenser in shunt with the separated switch contacts, the voltage of the charged condenser acts cumulatively with the voltage producing the current in the direct current circuit to divert the current through the shunt circuit including the condenser. Hence a large current can be quickly diverted from the arc through this shunt circuit. This diversion of current quickly reverses the charge of the condenser and at the same time extinguishes the arcing or electron emission discharge between the switch contacts. Thus when the condenser is fully charged in the reverse direction, the direct current circuit is effectively interrupted. The reversing of the charge of the condenser enables a condenser of relatively small capacity to be used to extinguish the arc or discharge of the vacuum switch. However, an uncharged condenser of sufficient capacity may be used to extinguish the arc or electron discharge between the vacuum switch contacts after they are separated. The important feature is to connect either the charged or uncharged condenser across the vacuum switch contacts after they have been separated a sufficient distance to insure that the arc or discharge cannot re-establish itself when once extinguished. The well-known expedient of connecting a condenser permanently across circuit interrupting contacts in order to absorb the energy in the circuit that otherwise would cause sparking or arcing has the inherent defect that the condenser becomes fully charged before the contacts are separated a sufficient distance to prevent the occurrence of sparking or arcing. This is due to the fact that the charging of the condenser requires only an almost infinitesimal time whereas the moving of the contacts a sufficient distance apart to prevent re-establishment of the sparking or arcing requires a relatively longer time. This difficulty is overcome, however, in accordance with the present invention by connecting the condenser across the contacts only after they have been separated the required distance. In this way no matter how rapidly the condenser is charged, the arc between the contacts is effectively extinguished at the instant of connection of the condenser thereacross.

Moreover, my present invention is not necessarily limited to the use of either a charged or uncharged condenser since other equivalent means may be employed for reducing the direct current to substantially zero value after the contacts of the vacuum switch have been separated. Thus a transformer may be connected in the direct current circuit and an alternating current superimposed upon the direct current in such a way as to reduce the current between the switch

contacts to zero value after the contacts have been separated to extinguish the arc or electron emission therebetween.

In the accompanying drawing Fig. 1 is a circuit diagram schematically illustrating a preferred embodiment of the present invention wherein a charged condenser is used with a vacuum switch for interrupting direct current and Fig. 2 is a schematic circuit diagram of a modified direct current vacuum switch interrupting arrangement utilizing a transformer for extinguishing the arc or electron discharge between the switch contacts.

The vacuum switch 10 illustrated diagrammatically in Fig. 1 may be of any suitable form in which the contacts 11 and 12 are separated within a highly evacuated container 13. As shown, the contact 12 is moved into and out of engagement with the stationary contact 11 by means of the electromagnetically controlled operating mechanism 14. Relative movement of the contact 12 within the container 13 is permitted by employing a flexible or yielding sylphon 15 for sealing the operating rod 16 upon which the movable contact 12 is carried to the casing 13. It will be understood that the most improved technique is employed in exhausting the casing 13 to a very high degree. Moreover, the contacts 11 and 12 and other parts within the casing should be specially treated to remove all occluded gases. This may be accomplished by heating the parts during exhaustion preferably by inductive action or by electron bombardment and the casing of the vacuum switch may be freed of gases by baking during exhaustion. The exhaustion of the casing 13 preferably is carried to a point where the vacuum is of the order of 1/100 of a micron pressure or better with all of the occluded gases removed.

The vacuum switch 10 is shown connected to control the establishment and interrupting of the circuit through which power is supplied from the direct current generator 17 to a suitable load indicated diagrammatically in the drawing, as the load resistor R1. It will be understood that means other than the vacuum switch 10 may be provided for establishing the circuit and the vacuum switch used only for interrupting the circuit if desired.

The operating mechanism 14 of the vacuum switch which may be of any suitable type is shown diagrammatically as of the type in which the toggle mechanism 18 is biased by the spring 19 to separate the contacts 11 and 12 of the vacuum switch. The toggle mechanism is held in the position in which the vacuum switch contacts 11 and 12 are in engagement by means of the latch 20. The releasing electromagnet 21 is connected to be energized in accordance with the current in the circuit and arranged to release the latch 20 to effect the separation of the vacuum switch contacts

11 and 12 upon the occurrence of an excessive overload current in the circuit.

As previously pointed out the action of the vacuum switch in interrupting the circuit depends upon the material of which the circuit interrupting contacts 11 and 12 are formed. When formed of a high melting point metal, the discharge therebetween involves thermionic electron emission due to the high temperature to which the contacts are raised. With low melting point material for the contacts the discharge between the contacts is of the type which is due to the formation of a cathode spot and accompanying ionization of the vaporized metal of the contacts. With the contacts of either high melting or low melting point material, the discharge or arc therebetween is effectively extinguished in accordance with the present invention by means of the condenser 22.

As shown in Fig. 1 one plate of the condenser 22 is permanently connected to the stationary contact 11 of the vacuum switch. The other plate of the condenser is connected through conductor 23 and the resistor R2 to be charged by the voltage applied to the load represented by the resistor R1. The conductor 23 also is connected to the stationary switch contact 24 having a cooperating switch contact 25 illustrated as carried by the operating arm 16 of the vacuum switch 10, the circuit extending through the switch 26 having a dashpot 27 or other suitable means for delaying the opening thereof. The arrangement is such that the time element contact 26 is maintained closed and the contact 25 is maintained out of engagement with the contact 24 when the vacuum switch 10 is in the closed position, as illustrated in the drawing, while the contacts 24 and 25 are brought into engagement during the separation of the vacuum switch contacts 11 and 12 and the contact 26 is released to open a time interval thereafter as determined by the time element device 27.

The operation of the invention in the form illustrated in the drawing is as follows: With the vacuum switch 10 closed, the direct current generator 17 supplies current to its load R1. The voltage of the generator 17 applied to the load R1 is also impressed upon the condenser 22 through the limiting resistor R2. In this way the condenser 22 is fully charged with the voltage and polarity of the charge corresponding to that of the generator 17, the polarities being indicated by the corresponding symbols + and -.

Whenever the contacts 11 and 12 of the vacuum switch are separated to interrupt the circuit either through operation of the overload releasing electromagnet 21 or by operation of the manual releasing handle 20a, an arc or discharge occurs between the vacuum switch contacts of the type depending upon the material of which the contacts are formed

as previously described. However, during the separation of the contacts the auxiliary contact 25 is brought into engagement with the cooperating contact 24 while the time element contact 26 remains closed. This connects the condenser 22 so as to impress the voltage of its charge on the arc or discharge between the vacuum switch contacts in opposition to the sustaining voltage of the arc or discharge between the vacuum switch contacts 11 and 12. The opposing voltage of the condenser 22 immediately neutralizes the voltage tending to maintain the arc or discharge between the vacuum switch contacts 11 and 12. As a result, the arc or discharge immediately is extinguished. Where the contacts are of low melting point material, the electron flow when once stopped cannot restart due to the immediate dissipation of the ionized metal vapor in the space between the contacts. Thus, when the current flow between the contacts is once stopped it does not restart and the circuit is maintained interrupted. It should be noted that the engagement of the auxiliary contacts 24 and 25 does not occur until after the contacts of the vacuum switch have been separated an appreciable distance. This insures that the discharge between the contacts is not re-established when it is once interrupted by the action of the condenser in the manner just described.

The limiting resistor R2 is of sufficiently high resistance to maintain the current from the generator 17 through the auxiliary contacts 24 and 25 at a minimum or negligible value since without such a high resistance in the circuit, the contacts 24 and 25 would in effect short circuit the generator. After the discharge between the vacuum switch contacts has ceased, the time delay contact 26 is opened thereby disconnecting the condenser 22 and the limiting resistor R2 from the negative side of the generator 17. If desired the time delay contact mechanism may be omitted and instead the contacts 24 and 25 may be arranged to make momentary sliding engagement only during the final portion of the movement of the operating rod 16 and thereby temporarily connect the condenser 22 across the vacuum switch contacts only long enough to effectively stop the electron discharge therebetween and then automatically open the circuit.

While the foregoing describes the operation of my invention from one aspect, it may be also considered from another aspect. That is, with the vacuum switch contacts closed and current flowing therethrough, the separation of the contacts causes an arc or electron emission discharge to occur between the contacts in the manner previously described. Upon the engagement of the auxiliary contacts 24 and 25 the current is diverted from the circuit including the vacuum switch con-

tacts into the shunt circuit around these contacts including the charged condenser 22. In this shunt circuit the voltage of the condenser is cumulative with respect to the voltage of the generator. Consequently a large value of current is quickly absorbed by the condenser and thus diverted from the arc or discharge between the vacuum switch contacts. This diversion of current in the shunt circuit including the condenser 22 quickly reverses the charge of the condenser so that the polarity of the plates is changed, the positive plate being now charged negatively and the negative plate being now charged positively. In this way the capacity of the condenser 22 is utilized to the greatest advantage since it is changed from the fully charged state of one polarity to the fully charged state of the opposite polarity.

Upon the reclosure of the vacuum switch 10 the contact 26 of the time element device is closed and the auxiliary contacts 24 and 25 are opened. Thus the condenser 22 is again charged in accordance with the voltage impressed upon the load resistor R1 preparatory to a subsequent extinguishment of the arc or discharge between the vacuum switch contacts as just described.

In the modified arrangement diagrammatically shown in Fig. 2, the vacuum switch 10' is connected to control the continuity of the circuit through which power is supplied from the direct current generator 17' to the load represented diagrammatically by the resistor R1'. In this arrangement a transformer T has its secondary winding 30 connected in series with the contacts 11' and 12' of the vacuum switch and its primary winding 31 connected to be energized from a suitable source of alternating current under the control of the auxiliary contacts 24' and 25' and also the switch 32, as indicated diagrammatically in the drawing.

The operation of this modified arrangement is as follows: Upon release of the toggle mechanism 14' either manually or automatically, the contacts of the vacuum switch are separated with a resulting arc or discharge established therebetween in the manner previously noted. Upon the engagement of the auxiliary contacts 24' and 25' the primary winding 31 of the transformer is energized from the alternating current source. This induces an alternating voltage in the secondary winding 30 of the transformer which is superimposed upon the voltage of the generator 17' in the load circuit. With the superimposed alternating voltage of a sufficient value the current in the load circuit is thereby brought to zero value or substantially to zero value at some point in one half wave of the alternating current. When this occurs the arc or electron discharge between the vacuum switch contacts is effectively extinguished and the direct current circuit interrupted.

With the direct current circuit interrupted at the contacts of the vacuum switch, the load on the secondary winding of the transformer is removed and consequently only magnetizing current is supplied to the primary winding. The switch 32 then may be operated to disconnect the primary winding of the transformer from the alternating current supply source. It will be apparent that a time element switch arranged to be operated in the same manner as switch 26 of Fig. 1 may be employed instead of the switch 32 if desired. The use of the transformer for reducing the current in the direct current circuit to zero value after the separation of the vacuum switch contacts may be advantageous under certain conditions, although the condenser arrangement shown in Fig. 1 is preferred.

While I have described and illustrated preferred embodiments of the invention it will be obvious to those skilled in the art that various changes and modifications may be made without departing from the spirit and scope of the invention, as set forth in the appended claims.

What I claim as new and desire to secure by Letters Patent of the United States, is,—

1. In combination, relatively movable switch contacts separable to interrupt a circuit, a condenser, and means for connecting the condenser across the contacts after a predetermined separation thereof to reduce the current between the contacts below the arc or discharge sustaining value.

2. In combination, a load circuit, an interrupter for the circuit having separable arcing switch contacts, a condenser connected to be charged responsive to the voltage impressed upon the load circuit when the interrupter contacts are closed, and auxiliary switch mechanism associated with the circuit interrupter for connecting the charged condenser across the arcing contacts upon a predetermined separation thereof to impress a voltage on the arc therebetween in opposition to the sustaining voltage of the arc.

3. In combination, a vacuum switch having contacts separable in an evacuated container to establish an electron discharge therebetween, and voltage impressing means effective upon a predetermined separation of the contacts for impressing a voltage between the contacts independent of the sustaining voltage of the discharge to suppress the electron discharge therebetween.

4. In combination, a vacuum switch having contacts separable in an evacuated container to interrupt the current in the circuit, a condenser, means for charging the conductor and auxiliary switch mechanism associated with the vacuum switch for connecting the charged condenser across the said contacts upon separation thereof to stop the flow of electrons between the contacts.

5. In combination, a load circuit, a vacuum

switch having separable contacts for interrupting the circuit, a condenser, connections between the condenser and the circuit whereby the condenser is normally charged in accordance with the voltage impressed upon the load circuit, and auxiliary switch mechanism associated with the vacuum switch and connections whereby the charged condenser is connected across the contacts of the vacuum switch with the voltage in opposition to the voltage of the discharge current therebetween upon a predetermined separation of the contacts.

6. The method of interrupting an electric circuit comprising separating conductors in the circuit to establish an arc or discharge therebetween and impressing a voltage on the arc or discharge independent of the arc or discharge sustaining voltage to extinguish the arc or discharge between the conductors.

7. The method of interrupting an electric circuit comprising separating conductors in the circuit to establish an arc or discharge therebetween and connecting a condenser between the conductors to extinguish the arc after the conductors have been separated sufficiently to prevent re-establishment of the arc.

8. In combination, a circuit interrupter having contacts separable for opening the circuit, means for separating the contacts, and means rendered effective upon a predetermined separation of the contacts for impressing a voltage on the arc or discharge between the separated contacts independent of the arc or discharge sustaining voltage to extinguish the arc or discharge between the contacts.

9. In combination, a circuit interrupter having separable contacts for opening a circuit, means for separating the contacts, means for establishing a circuit in shunt with the arc or discharge between the contacts upon a predetermined separation thereof, and means for impressing a voltage on the said shunt circuit independent of the arc or discharge voltage to extinguish the arc or discharge between the contacts.

10. In combination, a circuit interrupter comprising separable arcing contacts, means for separating the contacts to open the circuit, a shunt circuit for the current between the contacts, and means effective upon a predetermined separation of the contacts for impressing a voltage on the said shunt circuit to extinguish the arc or discharge between the contacts.

11. In combination, relative movable switch contacts separable to interrupt the circuit, and means connected upon a predetermined separation of the contacts in shunt relation with the gap therebetween for impressing a voltage on the gap to counteract the tendency of current to flow between the contacts.

12. The method of interrupting an electric circuit comprising separating conductors in the circuit to establish an arc or discharge therebetween and impressing a voltage between the conductors to extinguish the arc or discharge after the conductors have been separated sufficiently to prevent reestablishment of the arc or discharge by the circuit voltage.

10 In witness whereof, I have hereunto set my hand this thirteenth day of June, 1928.
